(57) **CLAIM**

The ornamental design for a mop handgrip, as shown and described.

DESCRIPTION

FIG. 1 is a perspective view of a mop handgrip showing my new design;

FIG. 2 is a front elevational view thereof, the rear elevational view being a mirror image thereof;

FIG. 3 is a left side view thereof, the right side view being a mirror image thereof;

FIG. 4 is a top plan view thereof;

FIG. 5 is a bottom plan view thereof; and,

FIG. 6 is a perspective view thereof.

The broken lines are for illustrative purposes only and form no part of the claimed design.

The stippled or dot pattern shading shown in FIGS. 2-5 represents shading and is not intended to be a surface design pattern.
